Primary Examiner—Doris V. Coles
Attorney, Agent, or Firm—D. L. Tschida

[57] **CLAIM**

The ornamental design for an audible fishing lure, as shown and described.

DESCRIPTION

FIG. 1 is a perspective drawing showing a top view of my lure design;

FIG. 2 is a left side elevation view thereof, the right side view being identical;

FIG. 3 is a front end view thereof;

FIG. 4 is a rear end view thereof; and,

FIG. 5 is a bottom view thereof.

The broken line showing of a simulated hammered pattern in FIGS. 1-5 is for illustrative purposes only and forms no part of the claimed design.
